INVENTOR

UNITED STATES PATENT OFFICE.

CASSIUS C. PALMER, OF OAKLAND, CALIFORNIA.

ICE-MAKING AND REFRIGERATING MACHINE.

SPECIFICATION forming part of Letters Patent No. 308,980, dated December 9, 1884.

Application filed February 15, 1883. (No model.)

To all whom it may concern:

Be it known that I, CASSIUS C. PALMER, of Oakland, in the county of Alameda, State of California, have invented certain new and 5 useful Improvements in Ice-Making or Refrigerating Machines, of which the following is a specification.

In the class of ice-making or refrigerating machines which use a volatile liquid or a gas as 10 a means of refrigeration, and which are constructed with two or more ice-making cells or refrigerating-chambers, great difficulty has been experienced, when all the cells or refrigerating-chambers were connected with one exhaust and condensing pump, in obtaining a 15 uniform degree of refrigeration in all the cells or chambers.

The object of my invention is to enable any 20 number of ice-making cells or refrigerating-chambers to be operated by a single exhaust and condensing pump and to maintain a uniform degree of refrigeration in all of them. I accomplish this object by connecting the exhaust-pipes from each ice-making cell or 25 refrigerating-chamber with a common receiver of any convenient shape, and this chamber I connect with the exhausting side of the pump. I prefer to make this chamber of such a form 30 that it will extend past each of the ice-making cells or refrigerating-chambers, and to give it a sectional area somewhat greater than the combined sectional area of all the exhaust-pipes from the cells or chambers which are connected with it.

To illustrate the nature of my invention 35 more clearly, I have shown it in the accompanying drawings as it may be arranged in connection with my improved ice-making machine patented May 18, 1880, No. 227,703.

In the drawings, Figure 1 is a side elevation 40 of one arrangement of my ice-making machine, with portions of the casing of the condenser and of the side of the freezing-tank broken away in order to show more clearly the positions of the various parts. Fig. 2 is an end elevation of the freezing-tanks, one of them 45 being in section.

Like parts in each figure are marked by the same letters.

In this apparatus the condensed refrigerating-liquid flows from the condenser G, Fig. 1, 50 through the pipe H, which extends along the

lower part of the freezing-tank A, and thence by the pipes I I into the freezing-cells B B, which are placed within the tank A, and there 55 it is volatilized or expanded suddenly into a gas or vapor. This sudden expansion produces the refrigeration of anything in the vicinity of the cells B. After expansion in B, the vapor is drawn through the pipes C C, &c., into 60 the chamber D, which in turn is connected with the exhaust side of the pump F by the pipe E. The pump F compresses the vapors which it has drawn from the chamber D into a liquid form in the condenser G, whence it 65 again follows the same course as before, and the operation of refrigeration becomes continuous as long as the pump F is worked.

Hitherto it has been the practice in ice-making and refrigerating machines of this class to 70 connect the exhaust side of the pump with the freezing-cells or refrigerating-chambers by pipes arranged in a manner similar to the arrangement of the supply-pipe H and the pipes I I, as shown in Fig. 1, and it has been found 75 that the refrigeration produced in the cells or chambers nearest the pump was much more intense than it was in the more distant ones, and that when it was attempted to operate a long series of these cells or chambers by one 80 pump the last on the line were cooled but slightly. This was caused by the fact that the pump acts with great power on the nearest cells, thus causing a rapid circulation of the refrigerant through them, while in the more 85 distant cells the effect of the pump is but slightly felt, and the circulation of the refrigerant is slow or almost ceases, according to the number of cells and their distance from the pump. 90

In the arrangement shown in Fig. 1 I have interposed the common chamber D, of comparatively large sectional area and capacity, between the freezing-cells B B and the pump, the result being a very uniform distribution of 95 the effects of the pump over all of the freezing-cells, and a very uniform degree of refrigeration in all caused by the uniform circulation of the refrigerant through all of the cells.

I am aware that the chamber D may be used 100 with advantage in machines in which other kinds of cooling and refrigeration are accomplished as well as in ice-making machines, and I do not limit my claims to ice-making ma-

chines alone. In two applications filed on the 30th day of December, 1882, I have described it in an atmospheric refrigerating-machine; but I did not there claim it as a distinct feature, reserving it for this application, because 5 I believed it to be even more useful in an ice-making machine than in an air-refrigerating machine.

I do not confine myself to the form of chamber shown in the drawings, nor to the arrangement or mode of connection there shown.

I am aware of the Patent No. 177,999, in which the exhaust-pump draws the vapor from a comparatively large sized gas-receiver, 15 which is connected to the freezers by a series of tubes, each tube corresponding in cross-sectional area with that of the aforesaid receiver; but this arrangement differs from mine, inasmuch as the same result occurs as 20 in the arrangement of parts before referred

to as being usually practiced, owing to the corresponding area in cross-section of the tubes and receiver shown in said patent.

What I claim, and desire to secure by Letters Patent, is—

In combination with an exhaust-pump and two or more refrigerating-compartments, the chamber D, located between the exhaust-pump and said refrigerating-compartments and connected thereto by passages of smaller area than 30 the refrigerating-compartments, said chamber being constructed of much larger area in cross-section than the area of the several connections, substantially as and for the purpose specified.

CASSIUS C. PALMER.
